UNITED STATES PATENT OFFICE

2,554,177

FLOOR FURNACE GUARD

Maurice W. Fink, Memphis, Tenn., assignor to Tennessee Fabricating Company, a Division of Allied Industries, Inc., a corporation of Tennessee

Application November 13, 1948, Serial No. 59,807

6 Claims. (Cl. 256—1)

1

This invention relates to guards for grating covered floor openings through which hot air from hot-air furnaces, particularly those of the floor furnace type, is discharged.

These gratings, or as they are ordinarily known, registers, particularly those used with floor furnaces, become at times dangerously hot to the touch and have caused serious burns. It should be noted, however, that in the floor furnace type the cold air of the room flows downward around the periphery of the grating so that the rim of the grating is ordinarily not excessively hot even though the center portion may be.

Numerous devices have been devised or proposed to effect protection, but few if any make any provision for size adjustment, and anchorage against displacement and overturning is so difficult that it usually is not availed of and accidents occur because of displacement. Also when they are properly anchored removal is difficult, and when removal is accomplished storage poses a major problem.

The objects of the present invention are:

To provide a guard which may be extended and adjusted for use and which may be compactly collapsed for storage;

To provide a guard which may be readily extended both laterally and longitudinally, and as readily again collapsed for storage;

To provide a guard which has a limited minor adjustment of its width relative to its length when extended for use; and

To provide a guard having extending portions engageable by guard adjustment with portions of the grating or grill for effecting anchorage against displacement and overturning.

The means by which the foregoing and other objects are accomplished, and the manner of their accomplishment, will readily be understood from the following specification on reference to the accompanying drawings, in which:

Fig. 1 is a side elevational view of the guard extended and anchored to a floor grating.

Fig. 2 is a corresponding elevational end view.

Fig. 3 is a plan view of the guard showing a fragmentary portion of the grating with which engagement is made.

Fig. 4 is a fragmentary enlarged scale sectional plan view taken on the line IV—IV of Fig. 1, showing one of the connecting members between the sides and ends of the guard; and

Fig. 5 is a similar fragmentary sectional plan view showing an identical connecting member joining other portions of a side and end.

Referring now to the drawings in which the various parts are indicated by numerals:

2

The guard comprises substantially identical sides 12, 14, and ends 16, 18, all of lazy tong type, each of which are made up of flat bars pivotally connected by rivets. The sides are each made up of bars 20, 22 and 24, which are pivotally connected together by rivets 26, 27 to form the lazy tong structures of the sides. In this structure the bars 20 and 22 are identical except that the bars 22 have portions 22A extending below the bottom lines of the remainder of the lazy tongs to form anchor portions. The ends are of less width than the sides and are made up of bars 28, 30 similarly connected by rivets 32, 33, into the lazy tong structure of the ends. The bars 28 are of identical length with the bars 20, and the bars 30 of identical length with the bars 24. The upper terminals of the end bars 28 and the upper terminals of the side bars 20 are respectively connected by rivets 34 and 36 to the legs of an angle shaped coupling member 38, and the lower terminals of the end bars 28 and lower portions of the side bars 22 above the extensions 22A of these latter bars, are similarly connected by rivets 40, 42 to the legs of identical coupling members 44. The pins 27 which connect the longitudinal terminals of the side bars 24 and the pins 33 which connect the lateral terminals of the end bars 30 are also used to effect connection of these terminals to the legs of additional coupling members 46.

In Figs. 1 and 3, a typical grill is shown which includes a frame 50 which is supported by the floor 52 and carries longitudinal ribs 54 and transverse ribs 56 which are assembled and integrated into a grating, the spacing of the transverse ribs being much greater than that of the longitudinal ribs.

The rivets securing the bars together are so set up that the guard may be easily extended or collapsed, and the rivets connecting the coupling members to the bars are looser fits. When the sides 12 and 14 are extended longitudinally the coupling members cause related broadening of the ends 16 and 18, and when collapsed cause current collapse of the ends. When so collapsed the guard becomes a compact bundle (not shown) having substantially the overall length of the longest bars 22 and is readily stored until it is again needed.

50 In installing the guard this bundle is opened out until the sides 12, 14 of the guard approach the length of the grating and the extending terminal bar portions 22A at one end of the guard are engaged between the frame 50 and the longitudinal grill ribs 54 at the sides of the grill, and beneath the transverse rib 56 at one end of the

grill. The terminal bar portions 22A at opposite ends of the sides are similarly engaged with the opposite end of the grill and so engaged the guard sides are further extended to lock the extending terminal portions beneath the transverse grill ribs 56.

Obviously extension or shortening of the sides brings a proportional widening or narrowing of the ends, but such minor widening as occurs after insertion of the bar portions in the grill to effect anchoring is readily taken care of by twist and shift of the coupling members 38, 44 and 46.

It will be apparent that the guard is of less length and width than the frame of the grill and even slightly less than the length and width of the grill proper. For all practical purposes however it substantially prevents access to the grill and because of the cooling action of the down draft of cool air around the periphery of the grill effects in practice an ideal barrier against access to dangerously hot portions of the grill, and it is obvious that the smaller size structure needed under the present construction as compared to those which entirely surround the grill is extremely advantageous.

It will be noted that the present structure has a side length of about one and one half times the end width and this ratio is maintained whether fully collapsed or fully extended. Obviously when a guard is needed which is extremely narrow with regard to its length a length to width ration of two to one or even more might be used, and a one to one ration is even more obvious.

I claim:

1. A guard for a floor grill, said guard comprising flat bars pivotally articulated at identically spaced pivot centers, into lazy tong type side and end structures having quadrilateral pattern, and including pivotally attached bars crossing and having portions continuing upwardly and downwardly outward respectively, beyond quadrilateral portions of said sides and ends to terminal-pivot centers in vertical alinement, establishing substantially rectangular said side and end structures, and coupling means pivotally attached respectively to complementary portions of said structures at said terminal-pivot centers joining said sides and ends, the downwardly and outwardly extending said bar portions only of said side structures being continued beyond and below their respective said terminal-pivot centers and

oppositely outward beyond the planes of said end structures to establish anchor portions for engagement with said grill.

2. A grill guard in accordance with claim 1, in which said sides and ends each include at least one quadrilateral.

3. A grill guard in accordance with claim 1, in which the length of said sides is one and one-half times the width of said ends.

10 4. A guard for a floor grill, said guard comprising flat bars pivotally articulated at equally spaced pivot centers, into lazy tong type side and end structures having quadrilateral pattern, and including pivotally attached bars crossing and having portions continuing upwardly and downwardly outward respectively, beyond quadrilateral portions of said sides and ends to terminal-pivot centers in vertical alinement, establishing substantially rectangular said side and end structures, and coupling means pivotally attached respectively to complementary portions of said structures at said terminal-pivot centers joining said sides and ends, said side structures at their respective opposite ends including anchor members extending downwardly below the level of said side and end structures and oppositely outwardly beyond the planes of said end structures, said anchor members comprising portions of bars of said side structures extending below their lower said pivot centers.

20 5. A grill guard in accordance with claim 4, in which said sides and ends each include at least one quadrilateral.

25 6. A grill guard in accordance with claim 4, in which the length of said sides is one and one-half times the width of said ends.

MAURICE W. FINK.
